JOHN M. DOUBLEDAY, OF MONTCLAIR, NEW JERSEY.

Letters Patent No. 75,875, dated March 24, 1868.

IMPROVEMENT IN TIPPING UMBRELLA-FRAMES.

The Schedule referred to in these Letters Patent and making part of the same.

TO ALL WHOM IT MAY CONCERN:

Be it known that I, JOHN M. DOUBLEDAY, of Montclair, county of Essex, and State of New Jersey, have invented a new and useful Improvement in the Method of Fastening Tips to the Ribs of Umbrella and Parasol Metal Frames; and I do hereby declare that the following is a clear, full, and exact description thereof, which will enable others skilled in the business to make and use the same, reference being had to the accompanying drawings, forming part of this specification.

Heretofore when it was desired to fasten a tip of brass or other metal upon the rib, it has been customary to leave the end of the wire smooth and plain, as shown below in Figure 1, employing a brass tip, as illustrated in Figure 2. This tip contained the eye to which the cover of the umbrella or parasol is stitched, and being hollow at one end, was slipped over the blunt wire, (see *a*, fig. 1,) and fastened thereto by swaging. The objections thereto, are, first, the cost of the tip so applied, and second, its liability to become detached.

By the process which I have invented, the original tip of the metal rib, as ordinarily made, is preserved, the nib and eye being formed in the wire itself, after the usual method, as shown in Figure 3. The extreme end, (marked *b*;) is closely covered or surrounded, (as shown by the red line,) by a sheet or foil of proper thickness, either of brass or other ductile metallic substance, or any material adaptable to the purpose, which is made fast to the wire by swaging or pressure. This leaves the original rib intact and strong, and the substance which is overlaid thereon having an irregular surface to hold to, will be less likely to become detached, and in event of coming off will still leave the eye remaining, and the covers properly fastened to the frames. By the employment of a variety of metallic or other substances, either in natural or artificial colors, or in plain or wrought shapes, the frames to which these tips are attached will be greatly ornamented.

Having thus described my invention, what I claim as new, and desire to secure by Letters Patent, is—

The covering or overlaying, with metals or other substances, the ends of ribs employed in umbrella or parasol-frames, substantially as and for the purposes set forth.

JOHN M. DOUBLEDAY.
